(57) **CLAIM**

The ornamental design for a chair, as shown and described.

DESCRIPTION

FIG. 1 is a front left perspective view of a chair showing our new design;

FIG. 2 is a rear right perspective view thereof;

FIG. 3 is a left side elevation view thereof, the right side being a mirror image;

FIG. 4 is a front elevation view thereof;

FIG. 5 is a rear elevation view thereof;

FIG. 6 is a top plan view thereof;

FIG. 7 is a front left perspective view of a second embodiment of a chair showing our new design;

FIG. 8 is a rear right perspective view thereof;

FIG. 9 is a left side elevation view thereof, the right side being a mirror image;

FIG. 10 is a front elevation view thereof;

FIG. 11 is a rear elevation view thereof;

FIG. 12 is a top plan view thereof;

FIG. 13 is a front left perspective view of a third embodiment of a chair showing our new design;

FIG. 14 is a rear right perspective view thereof;

FIG. 15 is a left side elevation view thereof, the right side being a mirror image;

FIG. 16 is a front elevation view thereof;

FIG. 17 is a rear elevation view thereof; and,

FIG. 18 is a top plan view thereof.

The broken lines in the drawings represent a symbolic break in the design. The appearance of any portions of the chair between the break lines form no part of the claimed design.

1 Claim, 18 Drawing Sheets
